CLAIM

The ornamental design for a holder for a boat winch handle, as shown and described.

DESCRIPTION

FIG. 1 is a perspective view of a holder for a boat winch handle showing my new design, the broken line showing is for illustrative purposes only and forms no part of the claimed design;

FIG. 2 is a side elevation view thereof;

FIG. 3 is an opposite side view thereof;

FIG. 4 is a top plan view thereof;

FIG. 5 is a bottom end view thereof;

FIG. 6 is a perspective view of a second embodiment thereof, the broken line showing is for illustrative purposes only and forms no part of the claimed design;

FIG. 7 is a side elevation view of the embodiment of FIG. 6;

FIG. 8 is an opposite side view of the embodiment of FIG. 6;

FIG. 9 is a top plan view of the embodiment of FIG. 6; and,

FIG. 10 is a bottom end view of the embodiment of FIG. 6.
